ERASER MOUNTING FOR PENCILS

Filed Sept. 15, 1944

UNITED STATES PATENT OFFICE

2,370,831

ERASER MOUNTING FOR PENCILS

George R. Averill, Birmingham, Mich.

Application September 15, 1944, Serial No. 554,196

8 Claims.

(Cl. 120—38)

The invention relates to pencils and it has particular relation to erasers therefor.

One object of the invention is to provide in the so-called automatic pencil, an improved means for mounting an eraser within the pencil and for projecting it exteriorly thereof when it is desired to use the eraser.

Another object of the invention is to provide an eraser for a pencil such as indicated wherein the eraser can be projected automatically through the side of the pencil.

Another object of the invention is to provide an improved pencil and eraser construction wherein the eraser may be projected exteriorly of the pencil from a normally concealed position therein merely by moving a manually operable element on the pencil.

Another object of the invention is to provide an attachment for ordinary wooden pencils in the form of a tubular element having an eraser normally concealed therein which may be projected exteriorly of the element when it is desired to use the eraser.

Other objects of the invention will become apparent from the following description, from the drawing to which it relates and from the claims hereinafter set forth.

For a better understanding of the invention reference may be had to the accompanying drawing wherein:

Figure 1 illustrates a pencil of the automatic type embodying one form of the present invention, with part of the pencil shown in cross-section to illustrate details of the invention;

Fig. 2 is a fragmentary plan view of the pencil shown by Fig. 1, with the eraser in its projected position;

Fig. 3 is a cross-sectional view taken substantially along the line 3—3 of Fig. 2;

Fig. 4 is a cross-sectional view on a larger scale taken substantially along the line 4—4 of Fig. 3;

Fig. 5 is a view illustrating application of the invention shown by Figs. 1 to 4 to an ordinary wooden pencil;

Fig. 6 is a view of another form of the invention embodied in an automatic pencil;

Fig. 7 is a fragmentary view of the pencil shown by Fig. 6 with the eraser in its retracted position;

Fig. 8 is a plan view similar to Fig. 7 showing the eraser in its projected position;

Fig. 9 is a cross-sectional view, on a larger scale, taken substantially along the line 9—9 of Fig. 8; and

Fig. 10 is a cross-sectional view on a larger scale taken substantially along the line 10—10 of Fig. 9.

Referring to Fig. 1, the pencil shown is of the automatic type and includes a barrel 10 having a tapered end 11 from which a lead 12 projects.

According to the present invention, the opposite

end of the barrel 10 has an eraser element mounted therein and this may comprise a tubular holder 14 in which an eraser 15 is fastened in any suitable way. The holder 14 may be constructed of thin sheet metal or the like and it is pivotally mounted on aligned pins 16 and 17 projecting inwardly from opposite sides of the barrel 10. These pins have slightly pointed or rounded inner ends which seat in similarly shaped indentations 18 and 19 formed in the side walls of the holder.

Normally, the eraser is disposed within the barrel in a concealed position but it is adapted to be projected outwardly through a socket opening 21 in the wall of the barrel when it is to be used. The eraser is normally urged outwardly by a spring 22 having one end 23 projecting into a radial slot in the pin 17 and its other end projecting axially of the pin as indicated at 24 into an opening in the holder 14. This spring is so arranged that it urges the eraser in a direction to cause it to move outwardly through the opening 22, and into the position shown in Figs. 3 and 4. A sleeve 25 slidably mounted on the barrel and over the opening 22 holds the eraser within the barrel and preferably a nib 26 is formed on the holder for contacting the inner surface of the sleeve. If the eraser is within the barrel and it is desired to use it, the sleeve 25 is moved to the right and as soon as the opening 21 is exposed sufficiently, the eraser is thrown or projected through the opening and into the position shown in Fig. 3.

For locking the eraser in its projected position, a slot 27 is provided in the side wall of the holder 14 for receiving the edge of the sleeve 25 and a similar slot 28 is provided for receiving the edge of the barrel at the left end of the opening 21. When the eraser moves outwardly, the slot 28 receives the edge of the barrel and then when the sleeve is moved, its edge enters the slot 27. The eraser now is firmly held in position and may be used without undesirable looseness. When the eraser is to be returned, the sleeve is moved to the right, then the eraser is swung against the action of the spring until it is within the barrel and then the sleeve is moved to its closing position. It will be noted that the barrel has an annular rib 30 for limiting movement of the sleeve to the right and that the left end of the barrel is enlarged as indicated at 31 to limit movement of the sleeve to the left.

If desired, the spring may be omitted and in this event the eraser could be moved outwardly by manipulating the pencil as by turning it to allow the eraser to gravitate outwardly. Also, the pivotal connection between the holder 14 and the pins 16 and 17 may be such as to allow removal and re-insertion of the eraser and holder in the event one wanted to separate the holder

from the pencil. Various means might be used for allowing this removal and insertion and in the particular construction shown, opposite sides of the holder have grooves or indentations 34 and 35 leading from the lower end of the holder to the recesses 18 and 19 receiving the inner ends of the pins. The inner ends of these grooves 34 and 35 are not as deep as the recesses 18 and 19 and therefore the ends of the pins normally will remain in the recesses. However, slight pulling movement of the holder 14 upwardly will cause the ends of the pins 16 and 17 to ride out of the recesses in a resilient manner and then to ride through the grooves 34 and 35. The holder may be reinserted by reverse movement causing the pins to ride through the grooves and into the recesses.

In the construction shown by Fig. 5, the invention described is applied to an ordinary pencil indicated at 40 and in this case, a short barrel indicated at 41 is provided which is slidable over the end of the pencil. Otherwise, the construction is the same as that described previously. If a positive stop is desired within the barrel to limit its movement over the pencil 40, this may be accomplished by means of an indentation in the side wall of the barrel or by fastening a pin therein.

In the construction shown by Figs. 6 to 10, inclusive, the holder and eraser are the same as previously described and are movable outwardly through the opening in the side of the barrel in the same manner. However, instead of using the sleeve 25 which is slidable along the barrel, a sleeve segment 42 is provided which is turnable over a barrel portion 43 of reduced diameter. The opening 21 is formed in this portion of the barrel. Locking of the holder in projected position is effected by providing a slot or groove 44 in the side of the holder which is adapted to receive the edge of the segment 42. In order to limit movement of the sleeve segment 42, a segment 45 of the barrel portion 43 is of larger diameter and this larger segment terminates in an edge 46 defining one edge of the opening 21 while the opposite edge provides a shoulder 47. The segment 42 may be maintained on the barrel by means of nesting, circumferentially extending beads 48 and 49 provided on the end of barrel portion 43 and the segment, respectively.

As seen in Fig. 10, the segment 42 may be turned counterclockwise a slight amount to allow the eraser and holder to be released and then the holder can be moved inwardly against the action of the spring so as to locate it within the barrel. After the holder is within the barrel the sleeve segment is turned until its edge engages the edge 46 of the barrel.

The construction shown by Figs. 6 to 10, inclusive, may likewise be used on an ordinary wooden pencil merely by providing a barrel portion which may be moved over the end of the pencil as described in Fig. 5. Likewise, the holder may be pivotally mounted on the pins 16 and 17 so as to permit removal and reinsertion. Furthermore, the spring may be omitted, in which event the holder could be projected out of the opening by manipulation of the pencil as previously mentioned.

Although more than one form of the invention has been illustrated and described in detail, it

will be apparent to those skilled in the art that various modifications may be made without departing from the scope of the appended claims.

What is claimed is:

5. A pencil having a socket and an opening in the longitudinal side of the pencil leading to the socket, and means for movably mounting an eraser in the socket so that it may be enclosed by the latter when not in use or be projected partly from the opening when it is to be used.
10. A pencil having a tubular portion provided with an opening in its side wall, and means for movably mounting an eraser in said portion so that it may be enclosed by the latter when not in use or be projected out through said opening when it is to be used.
15. A pencil eraser means comprising a tubular element provided with an opening in its side wall, means for movably mounting an eraser within the element so that it may be retained therewithin or be projected out through the opening when it is to be used, and cover means for closing the opening when the eraser is within the element.
20. A pencil eraser means comprising a tubular element provided with an opening in its side wall, means for movably mounting an eraser within the element so that it may be retained therewithin or be projected out through the opening when it is to be used, spring means for normally urging the eraser to the projected position and manually releasable means for holding the eraser within the element.
25. A pencil eraser means comprising a tubular element provided with an opening in its side wall, means for movably mounting an eraser within the element so that it may be retained therewithin or be projected out through the opening when it is to be used, spring means for normally urging the eraser to the projected position and a cover for the opening which is movably mounted on the element.
30. A pencil eraser means comprising a tubular element provided with an opening in its side wall, means for movably mounting an eraser within the element so that it may be retained therewithin or be projected out through the opening when it is to be used, spring means for normally urging the eraser to the projected position and a cover for the opening which is movably mounted on the element.
35. A pencil eraser means comprising a tubular element provided with an opening in its side wall, means for movably mounting an eraser within the element so that it may be retained therewithin or be projected out through the opening when it is to be used, spring means for normally urging the eraser to the projected position and a cover for the opening which is movably mounted on the element.
40. A pencil eraser means comprising a tubular element provided with an opening in its side wall, means for movably mounting an eraser within the element so that it may be retained therewithin or be projected out through the opening when it is to be used, cover means for closing the opening when the eraser is within the element and cooperative means on the mounting and cover means for holding the eraser firmly in its projected position.
45. A pencil eraser means comprising a tubular element provided with an opening in its side wall, means for movably mounting an eraser within the element so that it may be retained therewithin or be projected out through the opening when it is to be used, a cover slidably mounted on the element and normally closing the opening, and means on the mounting means and cooperative with the edge of the cover for holding the eraser firmly in its projected position.
50. A pencil eraser means comprising a tubular element provided with an opening in its side wall, and releasable means for pivotally mounting an eraser within the element so that it may be retained therewithin, or be projected through the opening when it is to be used or be entirely released from the element.
